UNITED STATES PATENT OFFICE.

GILES L. VREELAND, OF HARBERT, MICHIGAN, AND POMEROY P. VREELAND, OF BOZEMAN, MONTANA.

APPARATUS FOR ERECTING CONCRETE STRUCTURES.

1,173,991.

Specification of Letters Patent. Patented Feb. 29, 1916.

Application filed June 18, 1913. Serial No. 774,282.

To all whom it may concern:

Be it known that we, GILES L. VREELAND and POMEROY P. VREELAND, citizens of the United States, residing, respectively, at 5 Harbert, in the county of Berrien and State of Michigan, and Bozeman, in the county of Gallatin and State of Montana, have invented a certain new and useful Improvement 10 in Apparatus for Erecting Concrete Structures, of which the following is a full, clear, concise, and exact description, reference being had to the accompanying drawings, forming a part of this specification.

Our invention relates to the art of concrete construction and its object is to provide a method for erecting concrete structures, particularly concrete houses, and apparatus for carrying out our method.

Our invention provides for the erection 20 of concrete buildings having double walls at a comparatively low cost, the low cost being made possible for the reason that the erection of the walls may be rapidly accomplished inasmuch as it is unnecessary to 25 wait until the lower section, or sections, of the double wall has dried to any great extent before molding the next section, or sections, thereon, and inasmuch as almost all of the apparatus used in forming the walls may 30 subsequently be used upon the building for sheeting, etc., after said apparatus has been utilized in erecting the walls.

In the accompanying drawings illustrating our invention Figure 1 is a perspective view illustrating our molding devices in position for the pouring operation, certain parts of the mold boards being sectioned to more clearly reveal the apparatus; Fig. 2 is a cross-sectional view taken on the line 40 2, 2 of Fig. 1; Fig. 3 illustrates the mold boards in position upon the building footing or foundation ready for pouring the first double wall section, their raised positions being illustrated in dotted lines; and Fig. 4 is a somewhat modified embodiment 45 of our invention, wherein the inner and outer mold boards for the outer and inner walls, respectively, receive support from timbers extending from the footing or foundation through the space between the parallel walls.

Similar reference numerals refer to similar parts throughout the several views.

In employing our invention in the erection 55 of a concrete house we first form the concrete foundation or footing indicated at

5 in Fig. 3. It will not be necessary to burden this description by relating how this foundation is formed. When the foundation is completed and we are ready to proceed with the erection of the double wall, we place four sets of mold boards indicated at 6, 7, 8 and 9 upon the footing 5. The mold boards 6 and 9 may be retained in vertical position by securing the same by 60 means of clamps 10 to uprights 11. Spacing blocks 12 are interposed between mold boards 7 and 8 at the top and bottom and spacing blocks 13 interposed between the tops of the mold boards for each of the parallel walls. Wooden pins 14, having a diameter substantially equal to that of a lead pencil, are then interposed between the bottom portions of the mold boards for each of the parallel walls. The reason for having 65 these pins of such small diameter is the fact that they are left embedded in the molded concrete walls.

After the mold boards have been positioned and the various spacing blocks placed 70 in position as shown, large clamps or "bucks", indicated at 15, are positioned as shown and operated by driving wedges 16 between the upper ends of the clamping jaws thereof, thus exerting a pinching stress 75 upon the mold boards and spacing blocks and securing a perfectly rigid mold structure. After the pinching stress has been applied as aforesaid, concrete is poured 80 into the spaces between the mold boards 6 and 7 and mold boards 8 and 9. After the first sections of the double wall just molded have set, but not hardened, the clamps or "bucks" 15 are released and the spacing blocks 12 and 13 and the mold boards 7 and 8 are removed. A plurality of twisted 85 tie-rods 17 are then placed across the parallel walls just molded and suitable reinforcing L-bars 18 may be placed at the corners, if desired. The mold boards 6 and 9 are then unclamped from the uprights 11 and moved to the positions shown in full lines in Figs. 1 and 2 and in dotted lines in Fig. 3. The said mold boards are then 90 clamped to the uprights 11 and are so retained in their raised positions. It should be noted that when the mold boards 6 and 9 are in their raised positions the lower portions thereof slightly overlap the concrete walls therebeneath. In practice, we prefer 95 to have the boards overlap said walls about two inches. The mold boards 7 and 8 are

105

110

then positioned upon the tie-rods 17, as shown in Figs. 1, 2 and 3. It should be noted that the boards 7 and 8 are provided with a plurality of notches 7^a and 8^a, respectively, which receive the rods 17 and so permit the mold boards to overlap their adjacent concrete walls as indicated. The spacing blocks 13 are then interposed between the uppermost portions of the mold boards 10 6 and 7, and 8 and 9, and the spacing blocks 12 are again interposed between the mold boards 7 and 8. Owing to the fact that the mold boards overlap their adjacent walls as above described, it is unnecessary to space 15 the lower ends of the boards between which the concrete walls are molded. After the mold boards and spacing blocks have been positioned as set forth, the clamps or bucks 15 are again applied and the wedges 16 driven to clamping position. After the pinching stress has again been applied to the mold boards and spacing blocks, it will be readily seen that the weight of all the mold boards is carried by the uprights 11, 20 thus taking the weight of the molds off the soft walls therebeneath. This fact is very important, because we are thus enabled to position the mold boards for other wall sections and pour the concrete therefor 25 while the concrete walls therebeneath are yet very soft. Concrete is then poured into the mold boards as before, these several steps above set forth being repeated until the walls are as high as desired.

30 In Fig. 4 we have shown how we may modify our method by providing auxiliary uprights 11^a located in the space between the parallel concrete walls for supporting the boards 7 and 8. These uprights are 35 clamped to their respective mold boards by means of suitable clamps 10^a as shown.

The partitions in a building as a rule consist of single walls. In such cases our method is varied, in that the mold boards 7 45 and 8 are done away with and the spacing blocks are interposed between the boards 6 and 9. The pinching stress is then applied to the mold boards and the method carried out as in the construction of a double 50 wall.

55 From the above description it will be evident that by means of our improved method and apparatus we are enabled to mold two monolithic rings of concrete encircling the building for each vertical portion of the mold boards 7 and 8. During the period between the pouring of the concrete and the time that the concrete becomes "set" water is occasionally sprinkled upon the sides of 60 the mold boards not engaged by the concrete in order to prevent distortion of the mold boards by warping.

Our method of wall construction has a

particular advantage in that the only special 65 apparatus necessary is the bucks and the small clamps. After a concrete house has been erected, the mold boards may be used for sheeting and false flooring. Thus it is possible to use new mold boards for each 70 job without any undue wasting of lumber.

75 What we claim and desire to secure by Letters Patent of the United States is:

1. Apparatus for molding double concrete walls of the class described, comprising in 75 combination a pair of mold members for each wall, devices for supporting the inner mold member for the inner wall and the outer mold member for the outer wall above a previously formed section of double wall 80 and independently of said section, devices for spacing the mold members of each pair, separate spacing devices arranged to be interposed between the inner mold member for the outer wall and the outer mold member 85 for the inner wall and means for applying a transverse pinching stress to said mold members and spacing devices to firmly clamp the same together, whereby the weight 90 of the inner mold member for the inner wall and the outer mold member of the outer wall, the pinching means and a major portion of the outer mold member for the inner wall and the inner mold member for the outer wall is carried above and independently of the previously formed section of 95 double wall.

100 2. Apparatus for molding double concrete walls of the class described, comprising in combination a pair of mold members for each wall, timbers for supporting the outer mold member for the outer wall and the inner mold member for the inner wall above a previously formed section of double wall and independently of said section, clamps 105 for securing the last mentioned mold member to said timbers, devices for spacing said mold members from each other, and means for applying a transverse pinching stress to said mold members and spacing devices to 110 carry the major portion of the weight of the inner mold member for the outer wall and the outer mold member for the inner wall in suspension with the other mold members.

115 In witness whereof, we hereunto subscribe our names, in the presence of two witnesses.

GILES L. VREELAND.
